UNITED STATES PATENT OFFICE.

JOHN C. McLAUGHLIN, OF JERSEY CITY, NEW JERSEY, ASSIGNOR TO UNDERWOOD TYPE-WRITER COMPANY, OF NEW YORK, N.Y., A CORPORATION OF NEW JERSEY.

TYPE-WRITING MACHINE.

No. 889,855.

Specification of Letters Patent.

Patented June 2, 1908.

Application filed October 22, 1907. Serial No. 398,599.

To all whom it may concern:

Be it known that I, JOHN C. McLAUGHLIN, a citizen of the United States, residing in Jersey City, in the county of Hudson and 5 State of New Jersey, have invented certain new and useful Improvements in Type-Writing Machines, of which the following is a specification.

This invention relates to special paper-10 feeding devices of typewriting machines, such as shown in United States Patent No. 519,785, and in the pending application of Harry S. McCormack, No. 371,377, filed May 2, 1907, designed to facilitate the writing of 15 bills and simultaneously recording them, in a manner commonly known as "condensed charging."

The principal object of my invention is to provide improved, simplified and easily 20 operated means for producing spaces between the successive charges or entries upon the carbon record sheet, which as usual remains in the machine while successive bills are introduced, written and removed.

25 My invention is shown as applied to a mechanism such as is disclosed in said application, in which a crank is mounted upon the platen frame, but is normally out of engagement with the platen, a single swinging 30 movement of the crank serving to rotate the platen. The crank in said application is mounted loosely upon the platen axle, and a pawl or dog is pivoted upon the crank in position to engage a notched or toothed wheel, 35 the latter being fixed to the platen; a spring normally holding the pawl out of engagement with the notched wheel. A single movement of the crank throws the pawl into engagement with the notched wheel, such en- 40 gagement being mechanically maintained until the crank is swung back to normal position, whereupon the spring throws the pawl out of engagement with the toothed wheel, and also serves to hold the crank in its nor- 45 mal position.

According to my present invention, the 50 crank-operated dog is caused to skip one or more notches or teeth of the wheel during the initial portion of the initial stroke of the 55 crank (or other finger piece) and then to engage said wheel to turn it around, so that the platen is turned backwardly during the remainder of said stroke of the crank. The engagement of the dog with said wheel is also 60 maintained during the entire return move-

ment of the crank to normal position, so that the forward rotation of the platen effected by said wheel, is greater than the backward rotation thereof. Thus the platen is caused to turn backward a relatively short distance to 60 receive a bill, and then forwardly a relatively long distance to bring the bill to printing position; and in this manner a space is left between the carbon records on the long record sheet, which is retained in the machine 65 during the writing of successive bills, as understood in this art. That is to say, the record sheet is turned back with the platen through a certain arc to the point where a new bill is introduced, and is then turned 70 forward with the platen through a greater arc, so that the record of the new bill is separated by a space on the record sheet from the record of the immediately preceding bill. It is only necessary for the operator to manipulate the crank to and fro in order to produce 75 the required spacing between record entries, and hence confusion and mistakes are avoided, and the operation is much simplified.

80 In the accompanying drawings, Figure 1 is a perspective view, partly broken away, of a latch mechanism which causes one stroke of the platen to be shorter than the other stroke thereof. Fig. 2 is a part sectional plan of the 85 right-hand end of the platen frame and appurtenances of an Underwood typewriting machine, showing my improvements. Fig. 3 is an end elevation of the special platen-rotating mechanism, the crank being shown 90 as turning the platen. Fig. 4 shows a portion of the usual Underwood line-spacing mechanism at the left hand end of the frame. Fig. 5 is a perspective view of the crank and 95 a pawl pivoted thereto. Fig. 6 is a view like Fig. 3, but showing the crank in normal position, disconnected from the platen.

The usual cylindrical platen 1 of an Underwood typewriting machine is fixed upon an axle 2 journaled in the ends 3, of a platen 100 frame 5, the end of the axle projecting through the platen frame end and having a finger-wheel 6 thereon by means of which the platen may be rotated forwardly or backwardly to an unlimited extent. The platen 105 is also provided with the usual line-spacing devices, of which a toothed line-space wheel 7 and a yielding detent 8 therefor are seen at Fig. 4. Said line-space wheel is advanced intermittently by a pawl and lever, (not 110

shown). Upon the end of the platen axle is secured a hub or sleeve 10, upon which is rigidly secured a wheel 14 having teeth or notches 15 agreeing in number with the teeth 5 on the line-space wheel 7.

The wheel 14 is rotatable by means of a pawl 16 having a dog 17 to engage the teeth 15 of the wheel, but normally disengaged therefrom, as seen at Fig. 6, to permit independent rotation of the wheel 14 and the platen 1. Said pawl is pivoted at 18 to a crank 19 having a hub 20 to fit upon the outer end of the sleeve 10.

In order to effect backward rotation of the platen, the crank is swung from its normal rear position at Fig. 6 forwardly as at Fig. 3, the first portion of the movement of the crank causing the tooth 17 of the pawl to pass idly by one, two or three teeth of wheel 14, and then to move into engagement with said teeth. Said pawl carries a pin 21, which is normally pressed by a spring 22 into a recess 23 formed in a motionless disk-like member 24 mounted upon the outer portion 25 of the sleeve 10. When the crank starts forwardly, the pin 21 moves down out of the recess 23, and thereafter runs upon or within an annular guiding wall 25 formed in the face of the member 24 concentric with the platen axle 2, said wall acting to confine the pawl so that its dog 17 cannot escape from the wheel 14, and hence the platen must rotate backwardly and forwardly with the crank 19, which is provided with a handle 26.

The movements of the crank are limited by a stop 27 mounted upon an arm 28 which is also pivoted upon the sleeve 10. The stop is provided with a releasable pin 30 to engage any of a series of holes 31 formed in the member 24, the latter being prevented from rotating by means of a link 32 attached at 33 to the member 24 and at 34 to the platen frame.

The stop 27 having been set to the required position, as at Figs. 3 and 6, the handle 26 is grasped by the operator to swing the same towards the front of the carriage and downwardly. The movement of the crank 19 forces the pawl to engage the wheel 14, so that the latter and the platen are caused to rotate with the crank in a direction to turn the platen backwardly to receive a new bill, this motion of the platen continuing until the crank 19 is arrested by the stop 27. Upon the bill being inserted, the crank is swung through its return stroke back to initial position, the pin or projection 21 riding in contact with the guiding wall 25, which keeps the pawl 16 locked to the wheel 14. At the terminal portion of the return stroke of the crank, the pin 21 is engaged by spring 22 and snapped up into the recess 23, thereby releasing the wheel 14 and also arresting the crank.

It will be observed that the recess 23 is elongated and extends around the disk-mem-

ber 24 past several of the teeth or notches 15 of the wheel 14. The forward or leading end of this recess, however, is closed by a latch 35, pivoted at its rear end at 36 upon the disk-member 24, and caused by a spring 37 to close the forward portion of the recess, as shown in full lines in the drawings. At the initial portion or forward stroke of the crank 19, the dog-pin or projection 21 rides along the recess 23 behind said latch 35, and hence the dog skips several of the teeth or notches 15 of the wheel 14. When the pin 21 reaches the leading or forward portion of said recess, it encounters a cam or sloping portion 38 formed in the member 24, which, during the continued movement of the crank 19, forces the pin down out of said recess 23, said pin moving aside the latch 35, as seen in dotted lines at Fig. 3, and the dog 17 entering one of the notches 15 of the wheel 14; whereupon the crank, dog, wheel and platen rotate until the crank is arrested by the stop 27. Upon the return stroke of the crank, the pin 21 rides along the forward or under side of said latch 35, which forms substantially a continuation of the circular guiding wall 25, and hence the dog 17 is maintained in engagement with the wheel 14 and continues to turn the latter during the entire return stroke of the crank 19. Then the spring 22, which is in the path of the pin 21, snaps the latter up past the pivot end 36 of the latch 35, into the rear or lower end of the recess 23, the latter having an abutment 39 of proper form to arrest the crank. Owing to the idle initial movement at the initial stroke of the crank 19, the first stroke of the wheel and platen is rendered shorter than the second stroke thereof, and for this reason the record or carbon sheet, which is rolled around the platen, is advanced sufficiently to produce a blank space upon the records of successive bills thereon. Thus it will be seen, that by a single mechanism, provision is made whereby the operator needs only to grasp the crank, and swing it in a single direction about the platen axis 2, automatically effecting the locking of the crank to the platen, and maintaining such lock connection until the crank is swung back again as far as it will go, whereupon the first line of writing may be begun upon the bill, without attention from the operator to the matter of properly separating the records on the record sheet.

Variations may be resorted to within the scope of the invention:

Having thus described my invention, I claim:

1. In a typewriting machine, the combination with a revolvable platen and a notched wheel connected thereto, of a crank mounted to swing about the axis of said notched wheel, a dog carried by said crank for engaging with said notched wheel, said dog normally disengaged from the wheel, a pin upon

said dog, a circular guiding wall for engaging said pin to retain said dog in engagement with said notched wheel, said wall provided with an elongated recess, a latch covering the 5 leading portion of said recess, and means to cause the pin to enter said recess back of said latch; said latch being releasable by a forward movement of said crank.

2. In a typewriting machine, the combination with a revoluble platen and a notched wheel connected thereto, of a crank mounted to swing about the axis of said notched wheel; a dog carried by said crank for engaging with said notched wheel, said dog normally 10 disengaged from the wheel, a pin upon said dog, a circular guiding wall for engaging said pin to retain said dog in engagement with said notched wheel, said wall provided with an elongated recess, a latch covering the 15 leading portion of said recess, and means to cause the pin to enter said recess back of said latch; the recess being formed with a cam portion to enable the crank in its initial movement to force said pin to force aside 20 said latch and engage the dog with a notch of the wheel.

3. In a typewriting machine, the combination with a revoluble platen and a notched wheel connected thereto, of a crank mounted to swing about the axis of said notched wheel, a dog carried by said crank for engaging with said notched wheel, said dog normally disengaged from the wheel, a pin or projection upon said dog, a fixed disk having a circular guiding 30 wall for engaging said pin to retain said dog in engagement with said notched wheel, said wall provided with an elongated recess, a latch pivoted to said disk and normally caused by a spring to close the leading end of said recess, said latch forming a substantial continuation of said circular guiding wall, and a spring provided upon said disk in the path of said pin to force the latter during the return movement of said crank to enter said recess 40 back of said latch; the recess provided at its leading end with a cam to cause the pin to force the latch aside and engage the dog with a notch of the wheel.

4. In a typewriting machine, the combination with a revoluble platen, of a notched wheel connected thereto, a crank movable about the axis of said notched wheel, a dog mounted upon said crank, means limiting the reciprocation of the crank, means to engage the dog with one of the notches of the wheel, means to maintain the dog in operative engagement with said notch during both forward and backward throws of the crank, and a latch device for causing the dog to remain 50 longer in said notch at the return stroke than at the first stroke of the crank, to effect a substantially greater throw of the wheel and platen during the return stroke than during the first stroke of the crank.

5. In a typewriting machine, the combina-

tion with a revoluble platen, of a notched wheel connected thereto, a crank movable about the axis of said notched wheel, a dog mounted upon said crank, means limiting the reciprocation of the crank, means to engage 70 the dog with one of the notches of the wheel, means to maintain the dog in operative engagement with said notch while the crank is reciprocated, and a latch device for causing the dog to skip one or more notches or teeth of the wheel at the initial portion of the initial stroke of the crank, to render the backward rotation of the platen correspondingly shorter than the forward rotation thereof.

6. In a typewriting machine, the combination with a revoluble platen, of a notched wheel connected thereto, a crank movable about the axis of said notched wheel, a dog operable by said crank and movable into and out of engagement with said notched wheel, 80 and means including a latch mechanism for enabling said crank, dog and notched wheel to coöperate to effect at each complete reciprocation of the crank from and to its normal position, a short backward stroke of the 85 platen to receive a sheet, and a longer forward stroke of the platen to bring the sheet to printing position.

7. In a typewriting machine, the combination with a revoluble platen and a notched wheel connected thereto, of a crank mounted to swing about the axis of said notched wheel, a dog carried by said crank for engaging with said notched wheel, said dog normally disengaged from the wheel, a pin upon 95 said dog, a circular guiding wall for engaging said pin to retain said dog in engagement with said notched wheel, said wall provided with an elongated recess, a latch pivoted at one end and at its other end caused by a 100 spring to close said recess, said latch forming a substantial continuation of said guiding wall; and a gap being left between the pivot end of said latch and the other end of said recess, and a spring to cause the pin to 105 enter said gap and to travel behind said latch during the initial portion of the initial stroke of the crank; the recess being provided at its closed end with means to cause the pin to force aside the latch and the dog to engage 110 a notch of the wheel.

8. In a typewriting machine, the combination with a revoluble platen and a notched wheel connected thereto, of a crank having a limited movement and mounted to turn 120 about the axis of said wheel, a dog normally disengaged from the wheel, means for enabling the crank by a single movement to carry the dog idly around past a number of notches of the wheel and then to engage the 125 dog with the wheel, means to maintain the dog in such engagement during the remainder of the first stroke of the crank and during the entire return stroke of the crank, and means to disengage the dog from the wheel 130

upon the completion of said return stroke of the crank.

9. In a typewriting machine, the combination with a revoluble platen and a notched wheel connected thereto, of a crank mounted to swing about the axis of said notched wheel, a pawl pivoted upon said crank for engaging with said notched wheel, and normally disengaged from the wheel, a pin upon said pawl, a circular guiding wall for engaging said pin to retain said pawl in engagement with said notched wheel, said wall provided with an elongated recess, a latch pivoted at one end and at its other end caused 10 by a spring to close said recess, said latch

forming a substantial continuation of said guiding wall, and a gap being left between the pivot end of said latch and the other end of said recess, and a spring to cause the pin to enter said gap and to travel behind said latch during the initial portion of the initial stroke of the crank; the recess being provided at its closed end with means to cause the pin to force aside the latch and the pawl to engage a notch of the wheel.

JOHN C. McLAUGHLIN.
